UNITED STATES PATENT OFFICE.

THOMAS M. PRICE, OF RALEIGH, NORTH CAROLINA.

POSITIVE DRAFT KEY LOCK.

Application filed December 4, 1925. Serial No. 73,253.

This invention relates to means for retaining in operative position the keys generally employed on locomotives and freight cars for securing the couplers to the draft gear 5 yokes or links and fastening means for keys generally. Ordinarily these keys which extend horizontally through registering openings in the coupler and yoke are retained in position by a cotter pin or the like. Such 10 retaining means for the key has been found to be entirely inadequate, however, for the reason that the key will gradually work over to one side so as to bring the cotter pin into frictional contact with the edges of the 15 openings, thereby permitting the pin to be worn away with a consequent disengagement of the key and disconnection of the coupler from the yoke or link. It is therefore an object of the present invention to overcome 20 the foregoing difficulties by providing a draft key lock or clamp which may be readily attached to or removed from the key and which will in no way be affected by frictional contact with the edges of the 25 openings in the coupler or yoke.

Other objects and advantages of the invention will be apparent from the following description when taken in connection with the accompanying drawings, in which:

30 Figure 1 is a fragmentary plan view of a coupler and yoke with my improved key lock in place thereon.

Figure 2 is a section taken on line 2—2 of Figure 1.

35 Figure 3 is a section taken on line 3—3 of Figure 1.

Figure 4 is a perspective view of the key with the lock or clamp shown in position ready to be attached thereto.

40 Figure 5 is a section taken on line 5—5 of Figure 3, and

Figure 6 is a view similar to Figure 5 and showing the lock partly disconnected.

45 Referring to the drawings more in detail the numeral 1 indicates a portion of the draft yoke or rigging of conventional type and 2 the coupler which is ordinarily connected thereto by means of a horizontally slidable key somewhat similar to that shown in Figure 1 and in which a cotter pin is 50 employed as the retaining means.

55 In the present embodiment of the invention the numeral 3 designates the horizontally slidable key which is provided on one end with an abutment 4 adapted to engage

one side of the yoke 1 when the key is passed through the registering openings 5 and 6 of the yoke and coupler respectively.

The structure just described is all well known in the art and I will now describe the 60 novel modifications thereof, through the medium of which the difficulties hereinbefore referred to may be overcome.

The free end of the key 3, that is, the end 65 opposite the abutment 4 is provided with opposed notches 7 on its longitudinal edges, the bases of these notches being beveled off in the manner shown in Figures 5 and 6 for the purpose of allowing a necessary movement of the lock or clamp which will now 70 be described.

The lock, which may be a casting or the like, is substantially U-shaped in cross-section and comprises a base portion 8 and downwardly projecting legs 9 and 10. 75 These legs are adapted to be positioned in the notches 7 of the key while the base or body portion 8 is adapted to be flat against the key as shown in Figures 3 and 5. In order to prevent the locking element from 80 becoming accidentally disengaged from the key 3 one of the legs 10 is provided with a lug 11 which is adapted to engage the underside of the key; and it is because of this lug 11 that it becomes necessary to first 85 place the leg 10 in its notch 7 and then rock the lock in the manner shown in Figure 6 to the position shown in Figure 5.

An additional means for securing the lock in position is provided in the bolt 12 which 90 may be passed through the registering openings 13 and 14 of the lock and key respectively. Obviously, a cotter pin or the like may be substituted for the bolt 12 if desired.

From the foregoing description taken in 95 connection with the accompanying drawings it will be apparent that I have disclosed a lock for draft keys which cannot become accidentally displaced from its operative position, which may be readily applied and 100 detached, and which will resist the wear and tear to which it is subjected.

In accordance with the patent statutes I have described what I now believe to be the best embodiment of the invention, but it will 105 be understood that the mechanism depicted on the drawings is illustrative merely and not be taken in any limiting sense except in so far as these limitations may be set forth in the following claims.

Having fully described the invention what I claim as new and desire to secure by Letters Patent is:

1. In a device of the class described, the combination with an elongated flat key having opposed notches in its longitudinal edges, of a U-shaped locking element adapted to be operatively associated with said key with its legs positioned in said notches, and integral means for securing said locking element in place.
2. In a device of the class described, the combination with an elongated flat key having opposed notches in its longitudinal edges, of a U-shaped locking element adapted to be operatively associated with said key with its legs positioned in said notches, and a lug formed on one of said legs for engagement with the under side of said key.
3. In a device of the class described, the combination with an elongated flat key having opposed notches in its longitudinal edges, of a U-shaped locking element adapted to be operatively associated with said key with its legs positioned in said

notches, a lug formed on one of said legs at a distance from the base thereof substantially equal to the thickness of said key, the bases of said notches being beveled, whereby the leg carrying the lug may be first placed in its notch and the locking element then rocked so as to position the other leg thereof in its notch.

4. In a device of the class described, the combination with an elongated flat key having opposed notches in its longitudinal edges, of a U-shaped locking element adapted to be operatively associated with said key with its legs positioned in said notches, a lug formed on one of said legs at a distance from the base thereof substantially equal to the thickness of said key, the bases of said notches being beveled, whereby the leg carrying the lug may be first placed in its notch and the locking element then rocked so as to position the other leg thereof in its notch, and means for directly securing the base of said locking element to said key.

THOMAS M. PRICE.
